CLAIM

The ornamental designs for a combined coffee machine and coffee pot, as shown and described.

DESCRIPTION

FIG. 1 is a right perspective view of a combined coffee machine and coffee pot showing our new design;
 FIG. 2 is a left side view thereof;
 FIG. 3 is a rear view thereof;
 FIG. 4 is a top view thereof;
 FIG. 5 is a bottom view thereof; and,
 FIG. 6 is a front view thereof.

(Continued)

The broken lines depict portions of the combined coffee machine and coffee pot that form no part of the claim.

1 Claim, 6 Drawing Sheets
